DESIGN FOR A CAPE.

Design No. 6,634, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. 6,634, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The circular garment which forms the subject of my design is clearly shown by the accompanying photographic illustration. It is of the usual semicircular shape; is cut straight across at the top; has a semicircular recess and neck-band, *a*; is bound with a deep fringe, *b*, of the character represented; and is provided with a hood, *A*, of a triangular, or nearly triangular, shape, also bound with the fringe *b*, and which is cut down the center, and ornamented by a row of buttons, *c*, and double row

of gimp-like fringe *d*. At the lower end of the hood is a bow, *e*, with long pendent ends.

Irrespective of the colors employed, I claim—

1. The design for the hood *A*, with or without the fringe *b* and bow *e*.
2. The design for the whole garment, substantially as described, and as represented in and by the accompanying drawing.

In testimony whereof I have signed my name to this specification in the presence of two subscribing witnesses.

MARTIN LANDENBERGER, JR.
